DESIGN FOR A WOMAN'S UNIFORM CAP

Edith F. Scheppeler, New York, N. Y., assignor to Columbia Uniform Cap Corp., New York, N. Y., a corporation of New York

Application October 21, 1943, Serial No. 111,441

Term of patent 7 years

To all whom it may concern:

Be it known that Edith F. Scheppeler, a citizen of the United States and resident of New York city, in the county of the Bronx and State of New York, has invented a new, original, and ornamental Design for a Woman's Uniform Cap, of which the following is a specification, reference being had to the accompanying drawing, forming part thereof, in which,

Fig. 1 is a side elevational view of a woman's uniform cap showing my new design.

Fig. 2 is a top plan view thereof.

Fig. 3 is a front view thereof, and

Fig. 4 is a rear view thereof.

I claim:

The ornamental design for a woman's uniform cap, as shown.
